UNITED STATES PATENT OFFICE.

JENNIE DU QUETTE, OF CHICOPEE FALLS, MASSACHUSETTS.

DESIGN FOR A COLLAR-STAY FRAME.

41,586.

Specification for Design.

Patented July 11, 1911.

Application filed May 6, 1911. Serial No. 625,655. Term of patent 7 years.

To all whom it may concern:

Be it known that I, JENNIE DU QUETTE, a citizen of the United States, residing at Chicopee Falls, county of Hampden, and Commonwealth of Massachusetts, have invented a new, original, and ornamental Design for a Collar-Stay Frame, of which the following is a specification, reference being had to the accompanying drawing, which forms a part of this application and illustrates my design applied to a complete article of manufacture.

The actual article of manufacture is a stay-frame of sheet-material having the outline indicated in the drawing. The complete article is attached to the inside of a semi-transparent fabric collar for ladies' wear and embodies certain mechanical features which are the subject matter of my co-

pending application for mechanical Letters Patent, Serial No. 622659, filed April 22, 1911.

Independently of the mechanical features, I have embodied in the article of manufacture, a new and original design for the pair of stays 1 and 2. It is, of course, desirable that collar stays be entirely obscured from view, but this is impossible in conjunction with the semi-transparent collars, with which they are intended to be used.

I claim:

The ornamental design for a collar stay frame as shown and described.

JENNIE DU QUETTE,

Witnesses:

MABEL HOBART PAGE,
JOHN B. KNIGHT.
